UNITED STATES PATENT OFFICE

2,064,816

TREATMENT OF HYDROCARBON OILS

Otto Behimer, Chicago, Ill., assignor to Universal Oil Products Company, Chicago, Ill., a corporation of Delaware

Application October 22, 1932, Serial No. 639,035

2 Claims. (Cl. 196—60)

This invention particularly refers to an improved process and apparatus for the conversion of hydrocarbon oils of relatively wide boiling range, such as crude petroleum, wherein said oil is separated into a plurality of selected fractions, each of which is subjected to independently controlled conversion conditions most suitable for the production of maximum yields of good quality motor fuel.

10 As a further feature of the invention intermediate conversion products of the cracking operation are separated into fractions corresponding in boiling range to certain selected fractions of the charging stock and each fraction of said 15 intermediate conversion products is subjected to conversion together with the corresponding fraction of the charging stock.

In one of its more specific embodiments the invention may comprise heating a charging stock 20 such as crude oil or other hydrocarbon oil of wide boiling range and introducing it into a fractionating column wherein its substantial vaporization is effected and the vapors are separated by fractionation into three fractions comprising (1) 25 gasoline and naphtha having an end boiling point of approximately 400 to 450° F., (2) kerosene having an end boiling point of approximately 550 to 600° F. and (3) bottoms with an initial 30 boiling point of 550 to 600° F. and containing the fractions of the charging stock boiling above this point, subjecting the gasoline and naphtha fraction to reforming at a temperature of 950 to 1050° F. or thereabouts and a superatmospheric pressure of from approximately 500 to 1000 35 pounds per square inch, separately subjecting the kerosene fraction to a conversion temperature of 900 to 1000° F. or thereabouts at a superatmospheric pressure of approximately 300 to 500 pounds per square inch, separately subjecting the 40 bottoms to a conversion temperature of 850 to 950° F. or thereabouts at a superatmospheric pressure of approximately 100 to 300 pounds per square inch, separating the resulting vaporous and residual conversion products, subjecting the vapors to fractionation whereby a motor fuel of the desired boiling range and of high antiknock value is recovered as the final light distillate product of the system and whereby the higher boiling insufficiently converted components are 45 condensed as reflux condensate and the reflux condensate separated into fractions boiling above and below approximately 550 to 600° F., returning the low boiling fraction of the reflux condensate to further conversion together with the kerosene fraction of the charging stock and re-

turning the higher boiling fraction of the reflux condensate to further conversion together with the bottoms from the charging stock.

It should be understood that charging stocks of different characteristics may be separated into any number of different selected fractions, each of which requires separate treatment under different conversion conditions as provided by the features of the present invention, and the invention is therefore not limited to the separation 10 and separate treatment of any specific fractions but the operation may be varied to suit the requirements of the charging stock.

The accompanying diagrammatic drawing illustrates one specific form of apparatus in which 15 are embodied the features of the present invention, and the following description of the drawing includes a description of the operation of the process as it may be practiced in the apparatus illustrated.

20 Referring to the drawing, the crude oil or other charging stock of relatively wide boiling range is supplied through line 1 and valve 2 to pump 3, from which it is fed through line 4 and valve 5 into heating coil 6, which is located in a furnace 25 7 of any suitable form, by means of which the oil is heated to a temperature sufficient to insure its substantial subsequent vaporization at the desired pressure and the heated oil is discharged through line 8 and valve 9 into fractionating 30 column 10. The charging stock may of course be preheated in any well known manner not illustrated in the drawing prior to its introduction into the heating coil, when so desired.

35 The heated oil may enter fractionator 10 in substantially vaporized state, or is substantially vaporized in this zone, and when superatmospheric pressure is employed in heating coil 6 it is preferably released or substantially reduced in fractionator 10 in order to assist vaporization of 40 the oil.

The heated oil supplied to fractionator 10 is separated in this zone into any desired number of selected fractions which may be removed as an overhead vaporous stream, side streams from 45 suitable points in the fractionator, and as bottoms from the lower portion of the fractionator. In the case illustrated the charging stock is divided into three streams. The overhead vaporous product withdrawn from the upper portion of the 50 fractionator passes through line 11 and valve 12 to pump or compressor 13, by means of which it is supplied through line 14 and valve 15 to heating coil 16 wherein it is subjected to the desired optimum conditions of conversion temperature, 55

pressure and time, the required heat being supplied from furnace 17 of any suitable form. The heated products are discharged from heating coil 16 through line 18, valve 19 and line 39 into vaporizing chamber 41. That fraction of the charging stock removed as a side stream from fractionator 10 passes through line 20 and valve 21 to pump 22, from which it is fed through line 23 and valve 24 into heating coil 25 to be there subjected to the desired optimum conversion conditions of temperature, pressure and time with heat for the conversion reaction supplied from a furnace 26 of any suitable form. The heated conversion products are discharged from heating coil 25 through line 27, valve 28 and line 39 into vaporizing chamber 41. The remaining fractions of the charging stocks or bottoms are removed from the lower portion of the fractionator through line 29 and valve 30 to pump 31 to be fed through line 32 and valve 33 to heating coil 34, which is located in a suitable form of furnace 35, which furnishes the heat required to subject the oil in heating coil 34 to the desired conversion temperature under the optimum conditions of pressure and time. The heated oil is discharged from heating coil 34 through line 36 and valve 37 into a reaction chamber 38, which is preferably operated at a substantial superatmospheric pressure and which, although not illustrated in the drawing, is preferably well insulated to prevent the excessive loss of heat by radiation so that the oil from heating coil 34, and more particularly the vaporous products from the heating coil, may be subjected to continued conversion in this zone for a predetermined time while the liquid conversion products from the heating coil, which gravitate more rapidly to the outlet from the chamber, may be removed therefrom without being subjected to the continued conversion time afforded the vapors in this zone. Both vaporous and residual liquid conversion products are withdrawn from the lower portion of chamber 38 through line 39 and valve 40 into vaporizing chamber 41.

It will be understood that, although not illustrated in the drawing, the conversion products from heating coils 16 and 25 may also be subjected to continued conversion time in chamber 38 or in similar individual chambers not illustrated in the drawing. However, the low boiling nature of the fractions supplied to heating coils 16 and 25 or, more particularly, the absence of any appreciable quantity of high boiling or high coke-forming materials in these fractions usually obviates the necessity of discontinuing heating of the oil before the desired degree of conversion is completed and to complete the conversion, particularly of the vaporous components of the oil, in an unheated reaction chamber, which practice is desirable in the treatment of higher boiling oils in order to avoid coking of the heavy end products. The total conversion time required for the optimum treatment of the light fractions may therefore be allowed in the heating coils without employing a reaction chamber and this type of operation is the one illustrated in the drawing.

The total vaporous and liquid conversion products from heating coils 16 and 25, as well as from heating coil 34 and reaction chamber 38, are discharged as already described into vaporizing chamber 41, which is preferably maintained at a substantially reduced pressure relative to the pressures employed in the heating coils and the reaction chamber. The latent heat liberated by the reduction in pressure serves to effect further

vaporization of the liquid conversion products in chamber 41 and final separation of vaporous and residual conversion products is effected in this zone. The operating conditions of the process may be controlled to accomplish the recovery of any desired type of residual product in chamber 41 ranging from good quality residual liquid through the various stages of solid or semi-solid asphaltic or pitchy materials to substantially dry petroleum coke. Residual liquid, when produced, may be removed from chamber 41 through line 42 and valve 43 to cooling and storage or any desired further treatment. When substantially dry coke is the residual product of the process it may be allowed to accumulate in chamber 41, to be removed therefrom after the operation of the chamber is completed, and, when desired, a plurality of chambers similar to chamber 41, but not illustrated, may be utilized to provide additional space for the deposition of coke and may be either alternately or simultaneously operated. Line 42 and valve 43 may also serve as a means of introducing water, steam or other suitable cooling medium into the bed of coke in chamber 41 to hasten cooling and facilitate cleaning of the chamber.

Vaporous conversion products pass from chamber 41 through line 44 and valve 45 to fractionator 46, wherein their insufficiently converted components are condensed as reflux condensate and separated into selected fractions for the further treatment, as will be later more fully described, while vapors of the desired end boiling point, preferably within the range of motor fuel and of good antiknock quality, are withdrawn together with uncondensable gas from the upper portion of the fractionator through line 47 and valve 48, are subjected to condensation and cooling in condenser 49, from which the resulting distillate and uncondensable gas passes through line 50 and valve 51 to be collected in receiver 52. Uncondensable gas may be released from the receiver through line 53 and valve 54. Distillate may be withdrawn from the receiver to storage or to any desired further treatment through line 55 and valve 56.

In the case illustrated, the insufficiently converted components of the vapors supplied to fractionator 46 are withdrawn therefrom as two selected fractions, one of which is recovered as a side stream or streams from one or any number of a plurality of selected points in the fractionator such as provided by lines 59, 59' and 59'', controlled by valves 60, 60' and 60'', respectively, passing therefrom through line 57 and valve 58 to pump 61. This fraction of the reflux condensate or insufficiently converted components of the cracked vapors will correspond, in the case illustrated, to the boiling range of that fraction of the charging stock withdrawn as a side stream from fractionator 10 through line 20 and valve 21 to pump 22, as already described, and the two streams are commingled by directing the oil from pump 61 through line 62 and valve 63 into line 23, to be discharged therefrom, together with the commingled oil from pump 22, through valve 24 in line 23 into heating coil 25. In this manner corresponding fractions of both the charging stock and the intermediate conversion products are subjected to conversion under the optimum conversion conditions for fractions of this particular boiling range in heating coil 25.

The higher boiling components of the intermediate conversion products condensed in fractionator 46, preferably having an initial boiling

point corresponding to the initial boiling point of the bottoms from the charging stock, are withdrawn from the lower portion of the fractionator 46 through line 64 and valve 65 to pump 66, wherefrom they are fed through line 67 and valve 68 into line 32, commingling therein with the bottoms withdrawn from fractionator 10, as already described, and passing therewith to further conversion under the desired conditions in 10 heating coil 34.

It will be understood that, as already stated in connection with the separation of the charging stock into various fractions, the intermediate or insufficiently converted products of the cracking 15 operation may also be divided into any desired number of selected fractions which preferably correspond approximately in boiling range to various selected fractions of the charging stock and are each subjected to further conversion 20 together with said selected fraction of the charging stock of corresponding boiling range.

The temperature to which the charging stock is heated prior to its separation into selected fractions is sufficient to effect its subsequent substantial 25 vaporization without appreciable conversion and may range, for example, from 600 to 750° F. or thereabouts with any desired pressure in the heating coil, ranging for example from substantially atmospheric to 100 pounds or more per 30 square inch. The separating and fractionating column to which the heated charging stock is supplied is preferably operated at substantially atmospheric or relatively low superatmospheric pressure below 100 pounds or thereabouts per 35 square inch. The conversion conditions to which the various fractions of the charging stock and the corresponding intermediate conversion products of the process are separately subjected may range, for example, from 800 to 1100° F., preferably with substantial superatmospheric pressures in the various heating coils ranging, for 40 example, from 100 to 1000 pounds or thereabouts per square inch. Preferred conversion conditions of temperature and pressure for various specific fractions in a system such as illustrated 45 and above described have previously been mentioned. The reaction chamber, as already indicated, is operated at a substantial superatmospheric pressure which may be substantially 50 equalized with or somewhat reduced relative to that employed in the communicating heating coil. The vaporizing or coking chamber is preferably operated at a substantially reduced pressure relative to that employed in the reaction 55 chamber. The fractionating, condensing and collecting portions of the cracking system may be operated at a pressure substantially equalized with or somewhat reduced relative to the pressure employed in the vaporizing or coking chamber.

60 As a specific example of one of the many possible operations of the process of the present invention, the raw oil charging stock is a Smack-over crude of about 27° A. P. I. gravity, which is heated to a temperature of approximately 600° F. at a superatmospheric pressure of about 100 pounds per square inch and then introduced into the fractionating and separating column, from which gasoline and naphtha, kerosene and bottoms are separately withdrawn, the gasoline and 65 naphtha fraction, having an end boiling point of approximately 450° F. and comprising about 20 per cent of the charging stock, is subjected in a heating coil to a conversion temperature of approximately 1000° F. at a superatmospheric pressure of about 800 pounds per square inch and

the products are discharged into the reduced pressure vaporizing chamber. The kerosene fraction, amounting to an additional 22 per cent or thereabouts of the charging stock and having an end boiling point of approximately 600° F., is 5 subjected in a separate heating coil to a conversion temperature of about 975° F. at a superatmospheric pressure of approximately 500 pounds per square inch and the products are then introduced into the reduced pressure vaporizing chamber. Bottoms from the topping operation having an initial boiling point of approximately 600° F. are subjected in a separate heating coil to a conversion temperature of approximately 925° F. at a superatmospheric pressure of about 300 pounds per square inch and are discharged into a reaction chamber operated at about the same pressure, wherein their 10 vaporous components are subjected to continued conversion and from which the total vaporous and liquid products are discharged into the reduced pressure vaporizing chamber. The vaporizing chamber is operated at a superatmospheric pressure of about 50 pounds per square 15 inch, which pressure is substantially equalized in the succeeding fractionating, condensing and collecting portions of the cracking system. A distillate of about 400° F. end boiling point is collected as the final motor fuel product of the process from the fractionator of the cracking 20 system. The intermediate conversion products of the process condensed in the fractionator of the cracking system are separated into fractions boiling above and below approximately 600° F. The 400° F. to 600° F. fraction is returned 25 for further conversion to the same heating coil to which the kerosene fraction of the crude is supplied, and the remaining higher boiling fractions, having an initial boiling point of approximately 600° F., are returned for further conversion 30 to the same heating coil to which the bottoms from the crude oil topping operation are supplied. This operation may yield, per barrel 35 of charging stock, about 72 per cent of motor fuel having an antiknock value equivalent to an 40 octane number of approximately 78 and about 15 per cent of residual oil, the remaining 13 per cent, or thereabouts, being chargeable principally to uncondensable gas.

When the operation is conducted on a non-residuum basis, producing petroleum coke instead of liquid residue, the yield of motor fuel may be somewhat increased without depreciating its antiknock value and usually with a somewhat increased yield of gas.

55 I claim as my invention:

1. A process for producing motor fuel which comprises fractionating crude oil containing natural gasoline and separating the same into a vaporous fraction containing the natural gasoline and naphtha, an intermediate liquid fraction, and bottoms; independently subjecting the vaporous fraction, the liquid fraction and the bottoms to conversion conditions of temperature and pressure and subsequently commingling the 60 same, separating the commingled hydrocarbons into vapors and residue, fractionating the vapors independently of the charging oil and separating therefrom a light reflux and a heavy reflux, re-treating the light and heavy refluxes in admixture with said liquid fraction and bottoms respectively and finally condensing the fractionated vapors.

2. A process for producing motor fuel distillate which comprises fractionating crude petroleum 65

and separating therefrom a light fraction containing natural gasoline hydrocarbons, an intermediate fraction and a heavy fraction, independently subjecting the light fraction, the intermediate fraction and the heavy fraction to conversion conditions of temperature and pressure in separate heating zones, subsequently discharging the thus heated fractions into a separating zone and separating the commingled hy-

drocarbons into vapors and residue in the separating zone, dephlegmating the vapors independently of the crude petroleum undergoing fractionation and separating therefrom a light reflux and a heavy reflux, retreating the light and heavy refluxes in admixture with said intermediate fraction and heavy fraction respectively, and finally condensing the fractionated vapors.

OTTO BEHIMER.
